LOCKING CLOSURE

Filed Dec. 11, 1936

FIG.3.

FIG. I.

FIG.2.

The diagram shows a cross-section of a dental crown. The numbers indicate specific measurements: 16, 43, 32, 44, 37, 26, 39, 15, 10, 16, 1, 37, 10, 10, 10, 21, and 35. The numbers 16, 43, 32, 44, 37, 26, 39, 15, 10, 16, 1, 37, 10, 10, 10, 21, and 35 are distributed around the perimeter and interior of the crown cross-section.

LOCKING CLOSURE

Charles H. Nehls, Detroit, Mich.

Application December 11, 1936, Serial No. 115,298

2 Claims. (Cl. 70—165)

This invention relates to locking closures, and especially concerns covers for tanks and other receptacles. An important aim of the invention is to provide an improved locking cap, incorporating mechanism of simple, secure and tamper-proof character rendering the entire cap body, and all accessible portions thereof, freely rotatable when the cap is locked, such rotatability preventing removal of the cap.

10 A further object is the provision of such a locking cover, the working parts of which are effectively protected against the entrance of moisture, the danger of freezing and sticking of the parts in cold weather being thereby obviated.

15 Another object of the invention is the provision of such a cap adapted to be incorporated in a design of especially neat and attractive appearance. A further object is to provide in such a locking cap a body portion carrying the lock so arranged that when the cover is in place upon a container, the body portion may be clutched and released with respect to a concealed and inaccessible closure portion extending into the opening to be closed.

20 A further object is the provision of improved and simplified locking means for such caps, as well as improvement of the means for rotatably connecting the closure and cap portions.

25 Other objects and advantages will be apparent from the following description wherein reference is made to the accompanying drawing illustrating a preferred embodiment of my invention, and wherein similar reference numerals designate similar parts throughout the several views.

30 In the drawing:

35 Figure 1 is a bottom view of a cap incorporating the principles of this invention and suitable for use as a tank cover or the like.

Figure 2 is a diametric cross-section thereof.

40 Figures 3 and 4 are horizontal sections taken substantially on the lines 3—3 and 4—4 respectively of Figure 2 and looking in the direction of the arrows.

45 Figure 5 is a view in diametric cross-section and partly broken away, taken substantially at right angles to the plane of Figure 2.

Figure 6 is a perspective view of the closure section, partly broken away and with the pivotal attaching means removed but shown in position ready for insertion.

50 Figure 7 is a perspective view of the interior of the closure portion, one wall thereof being broken away; and

55 Figure 8 is a perspective view of the interior of the cap portion, with the closure portion removed.

Referring now to the drawing, which shows an embodiment of the invention especially suitable for the filler openings of fuel tanks, such as automobile petrol tanks and the like, reference character 10 designates the body portion of the cap, such body portion being shown as of more or less conventional belled external contour, centrally carrying an integrally cast downwardly projecting barrel portion 12 which constitutes the cylinder for the plug 15 of a tumbler lock, and 10 also rotatably supports a cup-shaped closure member 35, fitted over the bottom of the barrel. The plug is exposed at the top of the cap to receive a key, in the conventional manner, but a protecting key-hole cover 17 pivoted to the top of 15 the cap body and adapted to seat upon a ring-gasket 18 encircling the plug is provided to seal the lock cylinder against the access of moisture from the outside, and swingable laterally to afford access to the key-hole. The key-hole cover is 20 shown pivotally attached to the cap body 10 by means of a downwardly projecting boss 19 extending into the top of a bore (undesignated) in the cylinder portion 12. A pin or screw, as 21, carried by the boss, projects from the bottom of 25 the barrel through the counterbored lower end 32 of the bore and into the boss 19. In the counterbored portion 32 and beneath the head of the screw 21 a compression spring 23 encircling the screw is trapped, such spring acting to hold 30 the key-hole cover 17 yieldably seated against the gasket, which is somewhat depressed below the remainder of the top of the cap body, to tend to center the small swinging cover.

35 In the periphery of the barrel portion 12 near its top a groove 26 is provided, and the closure member is shown rotatably attached to the barrel by means of key elements 37 projected through slots, as 38, in the sides of the closure and into such groove 26 in the barrel. The body and barrel are preferably integrally cast, and the keys 40 may be provided with struck-up portions, as 39, to increase the friction of their engagement with the slotted portions of the closure member. When fully inserted, the extremities of the keys 45 project from the closure into the belled interior of the cover, such projecting portions being perforated to enable their removal by means of a suitable tool, but only when the inside of the cap is accessible.

50 From the flat bottom surface of the barrel a pair of guides 25 project downwardly in parallel relation to form a slideway for the radially shiftable lock bolt or detent 30. The bolt may be stamped of relatively heavy sheet metal, and its 55

shape and arrangement are best shown in Figures 3 and 8. As there indicated, it carries an integral pointed extremity 31 which is operative to lock together the body and closure portions of 5 the cover and is provided with a back taper, for a purpose which will presently appear. The bolt is projectable laterally from the bottom of the barrel 12 to engage between detent teeth 50 carried by the body, from which teeth it may be 10 retracted, to free the body portion for independent rotation, thus preventing removal of the cap. The enlarged rear portion of the bolt is retained between the guides 25 and actuatable by an eccentric pin 16 projecting from the lower end of the 15 lock plug into a slot 32 in the bolt. It will be appreciated that when the lock plug is rotated, by means of a suitably bitted key, the bolt or detent may be reciprocated to project and retract the same.

20 The inwardly projecting detent teeth 50 carried by the cupped closure member 35 are also integrally cast in place, and arranged at the inside bottom corner of the cup, as best shown in Figure 7. Each tooth has parallel sides, imparting an outward taper to the space between any two thereof. As shown in Figure 3, such outward taper cooperates with the back taper of bolt portion 31 in such fashion that torque applied to the cap body tends, by forcing the sides of the bolt 25 and adjacent tooth together (when the bolt is projected), to urge the bolt outwardly, thus insuring its maintenance in projected position.

From the outer surface of the closure member near the bottom, extend holding lug portions 41, 35 which constitute the projecting ends of a transversely disposed sheet metal strip 40, centrally carried by the closure near the bottom thereof and housed in an under-cut slot 42 in the bottom of such closure member, the slot being closed and 40 the lug strip held in place by a conformably shaped slide 43 fitted into the slot from one end. The lug portions 41 are adapted to cooperate with bayonet-type locking portions (unshown) carried at the neck or opening of the receptacle 45 to which the cover is to be attached, although it will be appreciated that screw-type or other suitable holding portions might be provided. The lug strip 40 also may act as a spring to hold 50 slide 43 in place, a central boss, as 44, struck up slightly from the surface of the strip 40 for engagement with an appropriately arranged depression (undesignated) in the slide, acting as a positive lock to retain the slide, as well as to provide a centering pocket upon the other side of 55 the strip for the apex of an inverted conical spring 45 trapped in an opening, as 46, in the bottom of the closure member. The opening connects slide-way 42 with the interior, and a cupped spring retainer, slidably fitted in such 60 opening, covers the base of the spring and bears upwardly against the bolt 30, holding the parts against rattling and serving as a slide for the bolt.

It will also be seen that when the bolt is projected, the closure member 35 and bayonet locking portions 40 may be turned as a unit with the

cap body, and that the greater the effort exerted upon the cap, the more firmly the bolt is projected, accidental release of the parts being thus impossible, while when the bolt is retracted, its point lies inside and free of the teeth 50, so that the entire cap body and barrel may turn freely with respect to the closure member 35, such position of the bolt corresponding to the locked position of the cap.

Preferably the closure portion 35 is so designed 10 as to fit deeply into the neck or opening of the container to which the cap is applied, to such extent, for example, as to seat the gasket 55 against the top of the neck or container, while the cap body extends down the outside of the neck 15 or lies close to the top of the container, making the closure portion inaccessible, and, by reason of the free rotatability of the cap body when the device is locked, irremovable save by the use of a 20 proper key.

What I claim is:

1. A locking cover construction comprising a cupped closure member, a body member rotatably connected to the closure member, locking means carried by and rotatable with the body 25 member, including a detent movable into and out of a position in detaining engagement with both of said members, said body member having a portion rotatably extending into the cupped closure member, said detent being slidably mounted between the bottom of said portion and the bottom of the closure member, inside the latter and outside the former, cooperating abutment portions between which the detent is slideable, carried both by said body portion which projects into the cupped closure member and by the cupped closure member, said detent being movable to and from bridging relation with the abutment portions to connect and disconnect the body and closure members, external lug-forming 40 means comprising a transverse member carried by and projecting at its ends from the closure member, said transverse member also being arranged at least partly between said closure member and said portion of the body member which 45 projects thereinto, and a spring arranged between said detent and transverse member for urging one against said body member and the other against the closure member, and also urging said body and closure members longitudinally with relation to each other.

2. In a lockable container closure of the type having an external belled body freely rotatable when the closure is locked, a cupped closure element rotatably attached to the body, said body 55 having a portion rotatably fitted into the closure element, said closure element having a substantially cylindrical wall and an outwardly extending thickened abutment portion at its top, within the belled body, forming a shoulder adapted to act 60 as an abutment for sealing means, and keying means also extending through said thickened portion to rotatably join the cupped closure portion to said interfitting portion of the body.
